ATTACHMENT BOX HOLDERS

Edward W. Stanton, Cranford, John Mracek, Roselle Park, and John Stein, Elizabeth, N.J., assignors to The Singer Manufacturing Company, Elizabeth, N.J., a corporation of New Jersey

Filed Sept. 30, 1957, Ser. No. 687,255

1 Claim. (Cl. 248—289)

The present invention relates to sewing machine carrying cases and more particularly to means for mounting attachment boxes inside the cover of sewing machine carrying cases, and the invention has for one of its primary objects to provide an improved device of this character.

Another object of the invention is to provide the combination of a sewing machine carrying case and an attachment box holder, the latter being arranged to position an attachment box in either of two selected positions.

A further object of the invention is to provide an improved means for positioning an attachment box in an accessible position or in a storage position as desired.

A still further object of the invention is to provide an improved means for housing a sewing machine and an attachment box in a carrying case whereby when the sewing machine is removed from the carrying case the attachment box can be removed through space originally occupied by the sewing machine.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in the art readily to understand the function, operation, construction and advantages of it when read in conjunction with the accompanying drawing in which:

Fig. 1 is an elevational view, partly in section, showing a sewing machine carrying case and an attachment box holder embodying the present invention.

Fig. 2 is a perspective view showing the attachment box holder of Fig. 1 disposed in attachment box storage position.

Fig. 3 is a perspective view of the same attachment box holder disposed in another position in which the attachment box is accessible and can be withdrawn from the holder, and

Fig. 4 is a reduced scale drawing showing the carrying case cover in position for removal of the attachment box.

In the preferred embodiment of the invention illustrated, there is shown a sewing machine carrying case 16 comprising a cover 17 which has a horizontal top-wall 18, two end walls 19 and 21, a front wall 22, and a rear wall 23. The two end walls 19 and 21 converge upwardly and the front and rear walls 22 and 23 also converge upwardly, thereby making the cover 17 in the form of a four sided truncated pyramid. The top wall 18 is provided with a pick-up handle 24, and lower portions of the two end walls 19 and 21 carry latch members 29 and 31, which are similar to the latches illustrated in U.S. patent application Serial No. 590,512, filed June 11, 1956. The left hand end (Fig. 1) of the carrying case cover 17 has a block 32, substantially square in cross section and extending from the front wall 22 to the rear wall 23. The latch member 29 has an elongated bolt 33 which passes through the block 32. Above the block 32, the left hand end of the carrying case cover 17 is

2

provided with a wooden strip 34, rectangular in cross section, and also extending from the front wall 22 to the rear wall 23. In addition, a small stop 36 is secured inside the cover 17 at the junction of the end wall 19 and the top wall 18, the stop 36 being located substantially half way between the front wall 22 and the rear wall 23.

A sewing machine 37 is housed within the cover 17, the machine 37 being held to the cover 17 by the latches 29 and 31 in a manner similar to the way in which the base member is held to the cover member of the sewing machine carrying case shown in U.S. patent application, Serial No. 459,351, filed Sept. 30, 1954, now Patent No. 2,856,726.

When the sewing machine 37 and cover 17 are in the position shown in Fig. 1, the latches 29 and 31 engage the base of the sewing machine 37 and make it possible to use the handle 24 to pick up and carry the carrying case 16 and the sewing machine 37 as a unit. When desired, the latches 29 and 31 may be opened thereby releasing the sewing machine 37 from the carrying case 16. Then the cover member 17 can be lifted free and clear of the sewing machine 37.

The present invention relates primarily to an attachment box 41 and to an attachment box holder 42. The attachment box 41, per se, as far as the present invention is concerned, may be conventional and has a body 43 provided with a hinged cover 44. The attachment box holder 42 has a U-shaped mounting bracket 46 made up of a central reach 47 and two arms 48 and 49. The reach 47 by means of two holes 51 and two screws 52 (only one being shown), is secured to one face of the wooden strip 34. The free end of each of the arms 48 and 49 carries an inwardly pressed pivot pin 53, and the arm 49 carries a post 54 at a location remote from the pivot pin 53.

In addition to the above, the attachment box holder 42 has a skeleton metallic receptacle or four-sided box-like body 56. Three sides of the receptacle 56 are formed by a U-shaped plate having a wall 57, an end 58 and a second end 59. A fourth side of the receptacle 56 is formed by a plate 61 having, on three of its edges, a flange 62 disposed at ninety degrees (90°) with respect to the plate 61. The pivot pins 53—53 enter holes 63—63 formed in the ends 58 and 59. The end 59 is provided with two outwardly pressed stop lugs 64 and 66 and also with a post 67, the posts 67 and 54 being connected by an over-the-center tension spring 68. An external portion of the plate 61 and the flange 62 are covered by a felt bumper, indicated by the numeral 69.

From the above it will be seen that the skeleton receptacle 56 has one end 71 which is completely open and a second or opposite end 72 which is open except for one of the flanges 62. A portion of the attachment box 41 enters the receptacle 56 by way of the open end 71.

In operation the device is used as follows. Assume that the sewing machine 37 and the attachment box 41 are both housed within the carrying case cover 17 in the manner shown in Fig. 1. Under these circumstances the sewing machine 37 occupies the right, central, and part of the left portion of the space within the cover 17, and the attachment box holder 42 and attachment box 41 occupy the remaining part of the left portion of this space. When it becomes desirable to use the sewing machine 37 and attachments (not shown) carried in the attachment box 41, the operator opens both latches 29 and 31. This permits the operator to lift the cover 17 from the sewing machine 37. Removal of the cover 17 from the sewing machine 37 evacuates that portion of the cover formerly occupied by the sewing machine. Then the operator places the cover 17 to rest on its rear wall 23 (Fig. 4). This makes the open bottom of the cover

17 accessible to the operator. Next, the operator reaches into that portion of the cover formerly occupied by the sewing machine 37 and grasps the attachment box 41, turning the same on the pivot pins 53—53 from the attachment box storage position shown in Fig. 2, and also shown by solid lines in Fig. 1, to the accessible position shown in Fig. 3, and also shown by dotted lines in Fig. 1. When the attachment box receptacle 56 is in the accessible position, the attachment box 41 may be removed by sliding it out of the open end of the attachment box holder. When the receptacle 56 is in the attachment box storage position, the box 41 cannot become removed from the holder 42 because of the flange 62 which extends across the attachment box holder. The over-the-center spring 68 maintains the receptacle 56 in either of the two selected positions in which it has been placed. The exact position of the two terminal positions of the receptacle 56 is determined by the lugs 64 and 66, the lug 66 being engaged by one side of the arm 49 when the receptacle 56 is in the attachment box storage position (Fig. 2), and the lug 64 being engaged by the other side of the arm 49 when the receptacle 56 is in the accessible position (Fig. 3). Should the cover 17 inadvertently be placed upside down the stop 36 prevents the attachment box 41 from becoming dislodged from the receptacle 56. Attention is also called to the fact that the receptacle 56 and the attachment box 41, in being swung from one position to the other, are turned through space originally occupied by the sewing machine 37.

When the sewing machine 37 and the attachment box 41 are to be housed in the carrying case 16, the attachment box 41 is placed into the holder 42 when it is in the position shown in Fig. 3. Then the holder 42 and

the box 41 are turned to the position shown in solid lines in Fig. 1. Thereafter the cover 17 is placed over the sewing machine 37 and lowered until the latches 29 and 31 engage the base of the machine 37. The felt bumper 69 prevents the holder 42 from marring the sewing machine 37.

Having thus set forth the nature of the invention, what we claim herein is:

- A sewing machine attachment box holder comprising
 10 a four-sided box-like body, said body including a U-shaped member providing one side wall and two end walls, a flat plate member providing the other side wall, said other side wall being opposite and parallel to said first side wall and said flat plate member having inturned marginal edges at its two ends to which the extremities of the end walls of said U-shaped member are secured and having another inturned marginal edge along one of its sides to provide an attachment box stop, a mounting bracket pivotally secured to said body, a pair of stops provided
 15 on said body and disposed to cooperate with said bracket to locate said box-like body in one of two predetermined positions, and spring means acting between said body and bracket to urge said holder in either one of its predetermined positions.
